United States Patent Office.

D. C. McNEIL, OF OSCEOLA, MISSOURI.

Letters Patent No. 79,374, dated June 30, 1868.

IMPROVED SYMPATHETIC INK.

The Schedule referred to in these Letters Patent and making part of the same.

TO ALL WHOM IT MAY CONCERN:

Be it known that I, D. C. McNEIL, of Osceola, in the county of St. Clair, and State of Missouri, have invented a new and improved Ink; and I do hereby declare that the following is a full, clear, and exact description thereof, which will enable those skilled in the art to make and use the same.

This invention relates to a new and improved ink, whereby the ink, when used on paper, is invisible, no writing or marks appearing until the paper is exposed to the fire, when the ink or writing immediately appears and shows as black-ink writing; or, if first put into water, and not held to the fire, the writing will appear, after which the fire will have no effect upon it, but the writing will disappear when the paper is dried, and will again appear when wetted, as at first, and as often as desired, by drying and wetting.

And the invention consists in composing the ink so as to produce this effect, and in the use of the following ingredients, viz:

Acidum sulphuricum, C P 3 i.

Aqua distillata, 3 iij.

Saccharum purum, 3ss.

This composition should be used with a quill-pen, and will be found invaluable in transmitting secrets, in time of war especially, as descriptions of forts, movements of troops, &c., may be transmitted without fear of discovery, as when the paper and ink are dry the paper appears perfectly blank.

I claim as new, and desire to secure by Letters Patent—

An ink composed of the ingredients and in about the proportions substantially as herein named and described.

The above specification of my invention signed by me, this 12th day of March, 1868.

Witnesses:

ED. P. BARTLETT,

D. P. SHIELD.

D. C. McNEIL.
